UNITED STATES PATENT OFFICE.

WILLIAM M. RAPP, OF PHILADELPHIA, PENNSYLVANIA, ASSIGNOR, BY DIRECT AND MESNE ASSIGNMENTS, TO RAPP-WAGMAN MANUFACTURING COMPANY.

LINOTYPE-MACHINE.

1,047,289.

Specification of Letters Patent. Patented Dec. 17, 1912.

Application filed August 17, 1910. Serial No. 577,640.

To all whom it may concern:

Be it known that I, WILLIAM M. RAPP, a citizen of the United States, residing at Philadelphia, in the county of Philadelphia 5 and State of Pennsylvania, have invented certain new and useful Improvements in Linotype-Machines, of which the following is a specification.

My invention relates to improvements in 10 linotype machines, and is more particularly designed as an improvement upon the construction disclosed in Patent No. 932,577 granted to me August 31, 1909, the object of the invention being to provide an improved 15 gage operated by the assembler slide through the medium of improved mechanism recording the length of the line of matrices as it is assembled.

A further object is to provide an improved 20 construction of this character which may be attached to the ordinary linotype machines in use, being readily substituted for the old constructions on the machines.

With these and other objects in view, the 25 invention consists in certain novel features of construction and combinations and arrangements of parts, as will be more fully hereinafter described and pointed out in the claims.

In the accompanying drawings: Figure 1, 30 is a front elevation illustrating the assembling mechanism of an ordinary linotype machine with my improvements in position. Fig. 2, is a top plan view of the mechanism 35 shown in full lines in Fig. 1. Fig. 3, is an enlarged view in elevation of the indicator operating mechanism with the dial removed. Fig. 4, is an enlarged end elevation. Fig. 5, is a view of the opposite end of the mechanism, and Figs. 6, 7, 8, 9, and 10 are views 40 of various details of construction.

Referring particularly to Fig. 1, a portion 45 of the frame 1, the elevator 2, and the star wheel 3 of an ordinary linotype machine are illustrated in dotted lines, and my improvements illustrated in full lines in their cooperative relation to the parts above referred to.

4, is the assembler slide which is made in 50 sections providing longitudinal slots 5 through which guide blocks 6 project to guide the sliding movement of the assembler

slide, and 7 is a spring bar for drawing the slide longitudinally to its starting point with its adjustable finger 8 against the star 55 wheel 3. This assembler slide is moved in the opposite direction as the matrices 9 and spacebands 10 are assembled and moved into position between the star wheel and finger 8. A toothed rack 11 is formed on the upper edge of the slide 4, and meshes with the teeth of a gear wheel 12, fixed to a shaft 13 having rotary mounting in the plate 14. On this shaft 13, a dial 15 is secured and spaced from the gear by means of a block 60 or sleeve 16, and this dial is provided with a scale around its periphery, beginning with zero and numbered up to twenty-nine, dividing the dial into thirty marks indicating picas. 70

On the plate 14, a curved strip 17 is fixed, is concentric with the dial 15, and is provided with a scale having twelve indicating marks dividing the same into points, the dial and the strip 17 constituting a vernier 75 gage, and the cooperating scales thereon indicate at all times the exact measurement of the line assembled.

On the front of the dial 15, a pointer 18 is supported on a turn button 19, and this 80 pointer indicates to the operator when he is approaching the length of line desired. The pointer 18 normally moves with the dial, but can be moved relative thereto by the turn button 19 in order to set the pointer 85 in different positions relative to the dial.

The dial 15 is preferably of bell metal, and is adapted to be engaged by a clapper 20 connected by a spring rod 21 with a pivoted block 22 pivotally connected to a 90 bracket 23 on plate 14. This block 22 is in the path of movement of a beveled trip 24 which is pivotally supported on a screw 25 which projects through the slot 5 in the assembler slide 4, and through an elongated 95 slot 26 in a catch 27. This trip 24 is pivotally mounted as above explained, so that it will operate the clapper 20 when the slide moves to the left, but will pivot when the slide moves in the other direction, and not operate the clapper. The movement of the trip is limited in one direction by a pin 24^a as clearly shown in Figs. 3 and 4. This catch 27 is provided at its upper edge with 100

teeth 28 to engage in the teeth of rack 11, and engage the gear 12 to prevent any further movement of the assembler slide. A forwardly projecting tongue 29 is provided at the lower end of the catch 27, and a coiled spring 30 is positioned between this tongue 29 and a block 31, which is recessed to accommodate the slide 4, and through which the screw 25 above referred to projects, trip 24 being located at one side of the block in front of the slide, and catch 27 located at the opposite side of the block in rear of the slide. The trip therefore serves to sound the alarm just before the catch reaches the gear and stops further movement of the slide, and by pressing the tongue 29 upward, the teeth 28 may be released from the rack 11 so that the trip may be located at any desired position on the assembler 15 slide in accordance with the length of line to be set up.

To brake the assembler slide, I employ a brake lever 33 which is pivotally supported between its ends on a screw pivot 34. One end of this lever 33 is bent upwardly and laterally as illustrated in Fig. 8, and projects into a bifurcated bracket 35, the two members of this bracket 35 having recesses 36 to receive the lower longitudinal member 30 of the assembler slide to straddle the same. The opposite walls of these recesses 36 are beveled as shown, so that when the bracket is in a vertical position, its sharp edges engage the slide and hold it against retrograde 35 movement, but when the lever 33 is pivoted so as to tilt bracket 35 slightly, the latter presents a wider surface to the slide and allows it to move rearwardly. The long end of this lever 33 is made with a bifurcated 40 bracket 37, and a lever 38 is fulcrumed between its ends on the screw pivot 34, and at one end is located in the bifurcated bracket 37. The opposite end of this lever 38 is located in the path of movement of the elevator 2, so that when the elevator moves upwardly to carry the assembled line of matrices, it will engage this lever 38 and the latter will move the bracket lever 33 so as to release the assembler slide and allow it to be 45 drawn backward by means of the spring 7. This brake 33 may also be operated by hand or foot power whenever desired, and is held in normal position by a spring 45.

A bracket 39 is fixed to the frame of the machine by means of a screw 40, and on this bracket 39 my improved spaceband supporting bar 41 is pivotally connected by a pin 42, said bar being normally held in horizontal position by means of an arm 43 on bracket 39, which limits its downward pivotal movement. This bar 41 in cross section, is of general inverted T-shape, that is, it is provided with a central longitudinal flange 44 extending throughout its length.

65 The spacebands in machines of this char-

acter are notched at their lower ends, and these notches are in the thin intermediate portions of the band. Bars to support these bands have been provided on machines of this character, but such bars engage the thin 70 intermediate portion of the bands, and soon wear the same, resulting in damage to the bands and shortening their lives. With my improved bar 41, the bands are supported on their thicker ends, and the flange 44, 75 while it projects up into the notches of the bands, does not bear against the thinner metal of the bands, and does not wear the same, yet it prevents lateral movement of the bands. This bar 41 projects through the 80 elevator, and is rocked on its pivot slightly by the movement of the elevator as the latter carries the assembled line upwardly.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In combination with the assembler slide 95 of a linotype machine, of rack teeth on the assembler slide, a vernier gage comprising a fixed scale, and a rotary dial having a scale thereon to register with the fixed scale, a gear wheel fixed to turn with the rotary dial of the vernier gage, said gear directly in mesh with the rack teeth, a pivoted clapper adapted to engage the back of the dial, and a pivoted trip adjustably mounted on the slide and constructed to operate said clapper, substantially as described.

2. In combination with the assembler slide of a linotype machine, of rack teeth on the assembler slide, a vernier gage comprising a fixed scale, and a rotary dial having a scale 110 thereon to register with the fixed scale, a gear wheel fixed to turn with the rotary dial of the vernier gage, said gear directly in mesh with the rack teeth, a pointer on the face of said rotary dial, a pivoted clapper adapted to engage the back of the dial, and a pivoted trip adjustably mounted on the slide and constructed to operate said clapper, substantially as described.

3. In combination with the assembler slide 120 of a linotype machine, of rack teeth on the assembler slide, a vernier gage comprising a fixed scale, and a rotary dial having a scale thereon to register with the fixed scale, a gear wheel fixed to turn with the rotary dial of the vernier gage, said gear directly in mesh with the rack teeth, a pivoted clapper 125 back of and hid by said dial, means on the slide to engage and operate the clapper to strike the dial, said means comprising a 130

pivoted trip adjustable on the slide, and
means forming a part of the trip support
adapted to be engaged by the gear and limit
the turning movement of the gear, as well
5 as the longitudinal movement of the slide,
substantially as described.

In testimony whereof I have signed my

name to this specification in the presence of
two subscribing witnesses.

WILLIAM M. RAPP.
